UNITED STATES PATENT OFFICE.

ALLEN E. J. LUCKHURST, OF RIDGEWOOD, NEW JERSEY.

NON-TOPPLING BLOCK.

1,080,640.

Specification of Letters Patent.

Patented Dec. 9, 1913.

Application filed July 18, 1912. Serial No. 710,243.

To all whom it may concern:

Be it known that I, ALLEN E. J. LUCKHURST, a citizen of the United States, residing at Ridgewood, in the county of Bergen 5 and State of New Jersey, have invented a new and useful Non-Toppling Block, of which the following is a specification.

This invention relates to sheave blocks in use with tackle in hoisting and lowering life 10 boats, and other weights; and the object of my invention is to provide a simple, cheaply-constructed, and efficient device, to insure the more perfect working of the blocks and tackle when not in engagement with a 15 weight, or boat; a further object being to provide a device of the character described which can be used with an ordinary block in common use without material, or any change.

As now used, it is common for the traveling 20 block to topple over and foul the ropes, or get the same twisted and mixed in a manner to render the operation of the blocks and tackle impossible.

It is the object of this invention to provide 25 simple and efficient means to avoid this, and that without involving much additional expense.

The invention is illustrated in the accompanying drawing in which—

30 Figure 1, is a perspective view of two blocks and the tackle, with my invention applied to one of the blocks; Fig. 2, is an end view of a block with my invention applied thereto, and showing a portion of the tackle 35 rope in position; and, Fig. 3, is a plan view of my device.

In the drawing like letters of reference refer to the same parts in each of the views.

In practice I provide a device *a*, for attachment to a block *b*, so constructed that it 40 may be secured to said block by screws, or bolts *c*, in a manner so that the rope *d*, may be rove through the apertures *e*, at each side of the device, and be separated by divisions *f*.

The device is preferably plate-shaped in form, as more particularly shown in Fig. 2. It may be formed of sheet metal, or of any suitable material; but is preferably made of 50 cast iron, brass, or the like; and when so made it is evident that the contour of the device may vary, but the essential features should be maintained which are the later-

ally-extending portions projecting outward from the block at each side and tangential 55 to the periphery thereof, and the apertures in these projecting portions through which the tackle rope may be rove whereby the rope is held in fixed position at a sufficient distance above the sheave to prevent the 60 block toppling when relieved of a load, and the consequent fouling of the rope.

Whether made of sheet metal, or a casting, the holes *h*, should be provided so that the device may be quickly attached to any 65 block now in common use.

The device should have sufficient weight to keep the ropes under tension, thereby insuring the more perfect working of the tackle when free from a load. This is of 70 considerable importance in handling life boats where it is impossible to use a detachable weight to keep the blocks and tackle in operative position, as is practised in lifting other weights.

75 While my device may be applied to a specially-constructed block, it is evident that it can be applied to blocks in common use thereby rendering the same non-toppling; and it will thus be seen that I have provided 80 a simple and efficient device for the purpose set forth, and one that can be manufactured and applied at small cost.

Having thus described my invention, what I claim as new and desire to secure by Letters Patent of the United States is—

The combination with a sheave block of a plate of sufficient weight to keep the ropes under tension, said weight being directly fitted upon and rigidly secured to the top of 90 said block and extending at each side thereof free from the block, each of said projecting portions being provided with a plurality of apertures corresponding in number with the number of sheaves in said block and 95 in alinement therewith, the walls of said apertures being adapted to engage the rope above said block, as and for the purpose set forth.

In testimony of which invention I have 100 hereunto set my hand.

ALLEN E. J. LUCKHURST.
